UNITED STATES PATENT OFFICE

2,313,450

PROJECTING APPARATUS

Isadore Ellis Neft, Los Angeles, Calif.

Application July 17, 1941, Serial No. 402,819

5 Claims. (Cl. 88—28)

This invention relates to a projecting apparatus which may be employed in a public vehicle for the display of names of streets or stations as they are approached by said vehicle to permit the passengers to be kept informed as to the whereabouts of the vehicle and at each time of display of a name of a street or station, an advertisement may be also shown and further the device may be employed for projecting illustrative information on the screen while a person is giving a lecture and may be employed for many other purposes.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a fragmentary vertical sectional view illustrating a portion of a vehicle and showing the application of the invention thereto.

Figure 2 is a sectional view taken on the line 2—2 of Figure 1.

Figure 3 is a vertical sectional view illustrating the projecting apparatus.

Figure 4 is a transverse sectional view taken on the line 4—4 of Figure 3.

Figure 5 is a transverse sectional view taken on the line 5—5 of Figure 3.

Figure 6 is a fragmentary perspective view illustrating one of the film holders and its mounting upon a portion of an endless belt or carrier.

Figure 7 is a detail sectional view illustrating a portion of the operating means for imparting a step by step movement to the endless carrier or belt.

Figure 8 is a front elevation illustrating another portion of the operating mechanism including an indicating means for showing to the operator the same matter appearing on the screen by the projecting apparatus.

Figure 9 is a side elevation illustrating the operating device shown in Figure 8.

Figure 10 is a transverse sectional view of the operating mechanism shown in Figures 8 and 9.

Figure 11 is an end elevation illustrating the screen on the casing.

Figure 12 is a vertical sectional view illustrating a modified form of my invention.

Figure 13 is a fragmentary perspective view illustrating one of the data carrying members

and a portion of the carrier employed in the modified form of my invention.

Figure 14 is a fragmentary longitudinal sectional view illustrating the modified form of my invention.

Figure 15 is a fragmentary vertical sectional view, illustrating another modified form of my invention.

Figure 16 is a sectional view, taken on the line 16—16 of Figure 15.

Figure 17 is a transverse sectional view taken on the line 17—17 of Figure 16.

Figure 18 is a fragmentary top plan view of the carrier.

Figure 19 is a vertical sectional view, showing one of the channel members of the carrier and the film frame pivoted therein.

Referring in detail to the drawings, the numeral 5 indicates a fragmentary portion of a public vehicle in which the present invention is mounted and is designated in entirety by the character 6. The invention is arranged in the vehicle so that the screen 7 thereof may be conveniently viewed by the passengers within the vehicle. As to the exact location of the invention 6 in the vehicle this is immaterial as long as it can be conveniently actuated by the operator of the vehicle and the screen viewed by the passengers.

30 A substantially L-shaped casing 8 is mounted in the vehicle 5 by a bracket 9 and is provided with a projector housing 10 thereon and which is in direct communication with the interior of the casing 8 by an opening 11. The housing 10 supports a projector 12 of any well known construction and the housing opposite the projector or lens thereof is equipped with a light opening 13 to permit the light rays from the projector 12 to shine upon the screen 7 mounted on the casing 8.

35 A lens fixture 14 may be mounted in the light opening 13, if desired, for focussing the light rays on the screen 7.

40 A plurality of rollers 15 is mounted in the casing 8 for the support of an endless belt or carrier 16. The purpose of constructing the casing 8 of L shape is to accommodate a carrier or belt of a maximum length and still not require a large amount of space for the accommodation of the casing. Also, a casing of this shape will permit one portion thereof to be lengthened to accommodate a longer belt or carrier. Of course, it is to be understood that the lengthening of the casing is carried out at the time of manufacture thereof.

The carrier or belt is preferably constructed of double thicknesses or superimposed layers of material and the outermost layer at spaced intervals of the belt or carrier is provided with loop portions 17 through which are extended rods 18 arranged transversely of the belt or carrier with the ends thereof projecting a considerable distance beyond the longitudinal edges of the belt or carrier. The ends of the rods which are of hollow formation are cut away, as shown at 19, to permit inserting in said ends angularly related ends 20 of spring arms 21 connected with film supporting frames 22. The frames 22 are so constructed as to clearly expose the matter on the films to the rays of light from the projecting device 12 and permit the rays of light to pass through the film onto the screen displaying on the screen the matter or information on the films.

The frames are of channel construction open at one end to permit the films to be placed in and removed from the frames as desired.

By referring to Figure 6 it will be seen that the film may bear the name of a street and also selected advertising matter or if the device is to be used for lecture purposes the film may have illustrative matter of the lecture thereon.

Coil springs 23 are connected to the spring arms 21 and to the belt or carrier acting to urge the frames 22 into position at right angles to the belt or carrier when freed of the walls of the casing. The opening 11 in the casing is to permit one frame at a time to enter the housing 10 and take a position opposite the light opening 13 so that the rays of light from the projecting device 12 can shine through the film of the frame.

By referring to Figure 3 it will be seen that the walls of the opening 11 are inclined which will permit the frame to gradually enter the housing 10 and to again return into the casing as the belt or carrier is advanced. The advancement of the belt or carrier is in a step by step movement through a manually actuated operating mechanism 24.

The operating mechanism 24 includes a slide 25 mounted in an offset 26 of the casing and which offset is provided with a slot 27 to permit an extension 28 to slide endwise of the horizontal portion of the casing. The slide 25 carries upstanding arms 29 to which are pivoted spring influenced hooks 30 capable of pivoting in one direction for the purpose of allowing the hooks 30 to ratchet past the ends of the rods 18 when the slide 25 moves to the right in Figure 3 under the influence of a spring 31. As soon as the hooks 30 pass a rod they assume a position to contact the rod and bring about a movement of the belt or carrier for a limited distance during the movement of the slide 25 in an opposite direction. This movement of the belt or carrier is sufficient to move the frame out of the housing 10 into the casing and to permit the following frame to enter and take the position of the preceding frame within the housing.

A flexible element 33 is connected to the extension and enters a housing 34 after passing over a guide pulley 35 and is connected to an operating lever 36 journaled on a shaft 37 located in the housing 34. A ratchet mechanism 38 is provided between the lever 36 and the shaft 37 for the purpose of rotating the shaft on the movement of the lever 36 in a downward direction when referring to Figure 7 and to permit

the lever to move free of the shaft 37 when moving upwardly.

A shaft 39 is also located in the housing 34 and the shafts have mounted thereon drums 40 on which is wound a web or belt 41 adapted to pass over guide rollers 41' in rear of a sight opening 42. The shaft 37 is journaled in the housing 34 and has its drum fixed thereto in any well known manner while the shaft 39 may be rotatable or non-rotatable and if non-rotatable in the housing the drum thereon will be rotatable relative to said shaft 39. The apron or belt 41 bears the same information as the various films on the carrier or belt 16 and whenever a certain name or information is on display the same will appear in the sight opening 42.

It is most preferable that the drum 40 on the shaft 39 be fixed thereto so that the shaft 39 can be rotated by a finger piece 44 arranged exteriorly of the housing 34 for rewinding onto the drum of the shaft 39 the belt after all of the films on belt or carrier have been displayed.

When the lever 36 is moved to its lowermost position it engages a circuit closer 45 of an electric circuit 46 for the purpose of actuating an alarm 47 for the purpose of attracting the passengers' attention to the matter being displayed.

Thus it will be seen that the operator of the vehicle on approaching a street can, through the actuation of the lever 36, bring the film bearing the name of the street in position to be projected on the screen 7 and at the same time an alarm will be given to attract the passengers' attention thereto.

While I have principally described the use of this invention in a vehicle it is to be understood that it can be used for many other purposes.

When it is desired to remove any one of the film frames from the belt or carrier, it is only necessary to unfasten the springs attached to the spring arms thereof and move the angularly related ends of said arms out of the ends of the rods. Of course, to accomplish this the housing 10 must be removed from the casing. The purpose of removing a frame is to permit the film to be replaced by another.

Referring in detail to the modified form of my invention as shown in Figures 12 to 14, inclusive, an elongated housing 48 is provided and one end wall thereof carries a lens mechanism 49 opposite a screen 50. A projecting device 51 is mounted in the housing 48 so that the rays of light therefrom may pass through the lens mechanism 49 onto the screen 50.

Also located in the housing 48 is an endless track 52 engaged by a series of rollers 53 over which is supported an endless carrier 54 including a plurality of pivotally connected blocks 55 provided with slots 56 to removably receive the headed ends of supporting rods 57 carrying film frames 58. The blocks 55 are further provided with projections 59 to be engaged by the hooks of the operating mechanism 24. As the carrier 54 is advanced in a step by step movement the various films will be brought into position between the projector and the lens mechanism 49 so that the matter on the films will be displayed on the screen 50.

Referring to my modified form of the invention as shown in Figures 15 to 19, inclusive, a casing 60 is provided in which is mounted an endless carrier 61 similar to the carrier 54 and the casing includes an opening 62 over which is formed a housing 63. The housing accommodates the projecting device as well as having the lens carry-

ing opening, as clearly shown in Figure 15. The endless carrier 61 consists of a plurality of pivotally connected channeled block-like members 63' including rollers adapted to travel on a track 64 which is located in the casing 60. The carrier 61 is advanced in a step by step movement by the operating means 24, the member 63' thereof having lugs 65 to be engaged by the hooks of the operating means.

Supporting rods 64' are pivotally mounted within the channel members and are spring influenced, as shown at 67, to normally assume a position extending outwardly of said channeled members and thereby move into position of placing the film frames 68 thereof in the path of the rays of light from the projecting device. Normally the film frames and the supporting rods thereof lie within the channeled members and are releasably retained therein by pivoted latch members 69 engaging keepers 69 on the film frames. The latch members 68 are spring influenced to sustain them in latching position against stops 70.

When the film frames lie within the channeled members they are in their inoperative position and also maintain this position when traveling in the casing, consequently permitting the casing to be constructed much lower than the form of my invention shown in Figure 12. When the channeled members move below the opening 62 a trip member 72 engages the latch members freeing the film frames to assume operative position, that is, extending through the opening into the housing 63 and thereby position the films in the path of the rays of light from the projecting device. It is to be understood that the film frames move into operative position one at a time as the carrier is advanced in a step by step movement as heretofore described.

The trip member 72 is formed on the casing in such a position to actuate the latches just before the channeled members assume a position under the opening 62 of the housing 63.

The casing 60 is provided with a cam 73, the purpose of which is to engage the film frames and swing them downwardly in their respective channeled members to assume inoperative position as they move from an operative position within rays of light from the projecting device.

While the casing 60 and housing 63 are shown in a general way in Figures 15 and 16, it is to be understood that the casing and housing are of such a construction that access to the interior thereof can be readily had when desired. This can be easily accomplished by constructing these parts of sections and detachably connecting them.

In the form of my invention shown in Figures 1 to 4, inclusive, the film frames may be caused to assume operative positions within the housing 10 by gravitation eliminating the use of the springs 23 by reversing the location of the housing 10 on the casing, that is, placing the housing 10 on the under side of said casing as well as the opening. Then the film frames may assume operative positions by gravitation through the opening into the housing 10 and to be returned to inoperative positions when advanced with the belt or carrier. Of course, in this instance the casing 8 would be of elongated formation instead of L-shape as previously described. Also, it will be understood that the screen 7 would be located on the under side of the casing 8.

While I have shown and described the preferred embodiment of my invention, it will be understood that minor changes in construction, combination and arrangement of parts may be

made without departing from the spirit and scope of the invention as claimed.

Having thus described the invention, what I claim is:

1. In a projecting apparatus, a casing, a projecting device carried by said casing, a screen positioned in the range of said projecting device, an endless carrier carried by said casing, a plurality of film frames on said carrier and movable one at a time thereby within the range of the projecting device and the screen, films bearing display matter mounted in said frames, means for operating said carrier and comprising a manually operated slide, a pivoted hook carried by the slide and engaging a part of the carrier upon operation of the slide in one direction to move the carrier in a step-by-step movement and a telltale display means operated by said first means to inform the operator of the display matter projected on the screen.
2. In a projecting apparatus, a casing, a projecting device carried by said casing, a screen positioned in the range of said projecting device, an endless carrier carried by said casing, a plurality of film frames on said carrier and movable one at a time thereby within the range of the projecting device and the screen, films bearing display matter mounted in said frames, means for operating said carrier and comprising a manually operated slide, a pivoted hook carried by the slide and engaging a part of the carrier upon operation of the slide in one direction to move the carrier in a step-by-step movement, a telltale display means operated by said first means to inform the operator of the display matter projected on the screen, and an alarm means actuated by said first means on each operation thereof.
3. In a projecting apparatus, a casing having an opening, a housing overlying said opening, a projecting device carried by said housing, a screen within the range of the projecting device, an endless carrier mounted in said casing, rods carried by said carrier and mounted for hinging movement thereon, spring arms removably engaged with the ends of said rods, frames carried by said spring arms, films in said frames and removable therefrom, spring means connected to said arms for urging said arms into position of placing the films and frames one at a time within the housing within range to the projecting device on the movement of the carrier, and means for imparting a step by step movement to the carrier.
4. In a projecting apparatus, a casing having an opening, a housing overlying said opening, a projecting device carried by said housing, a screen within the range of the projecting device, an endless carrier mounted in said casing, rods carried by said carrier and mounted for hinging movement thereon, spring arms removably engaged with the ends of said rods, frames carried by said spring arms, films in said frames and removable therefrom, spring means connected to said arms for urging said arms into position of placing the films and frames one at a time within the housing within the range of the projecting device on the movement of the carrier, a slide slidably mounted in said casing, members on said slide, and spring influenced hooks pivoted on said members to engage the rods on movement of the slide in one direction and to ratchet over said rods on movement of the slide in a reverse direction, spring means acting to urge the slide in the latter-named direction, and an operating means connected to the slide.

5. In a projecting apparatus, a casing having an opening, a housing overlying said opening, a projecting device carried by said housing, a screen within the range of the projecting device, an endless carrier mounted in said casing, rods carried by said carrier and mounted for hinging movement thereon, spring arms removably engaged with the ends of said rods, frames carried by said spring arms, films in said frames and removable therefrom, spring means connected to said arms for urging said arms into position of placing the films and frames one at a time within the housing within range of the projecting device on the movement of the carrier, a slide slidably mounted in said casing, members on said slide, spring influenced hooks pivoted on said

members to engage the rods on movement of the slide in one direction and to ratchet over said rods on movement of the slide in a reverse direction, spring means acting to urge the slide in the latter-named direction, a flexible element connected to the slide, a hand lever connected to the flexible element, a shaft rotatably supporting the lever, a housing supporting said shaft, a ratchet mechanism between the lever and the shaft, a second shaft in the second-named housing, said second-named housing having a sight opening, an apron bearing the data of the films movable relative to the sight opening by the operation of the lever, drums on said shafts and having the apron wound thereon and movable from one drum to another.

ISADORE ELLIS NEFT.
